UNITED STATES PATENT OFFICE

FRANCIS N. WOODMAN, OF CLINTON, MASSACHUSETTS, ASSIGNOR TO WICKWIRE SPENCER STEEL COMPANY, OF NEW YORK, N. Y., A CORPORATION OF DELAWARE

CONVEYER BELT

Application filed July 27, 1928. Serial No. 295,808.

This invention relates to a spiral wire conveyer belt such as is used in many industries for moving material from place to place or for supporting material during drying or other operations.

It is one object of my invention to provide a wire belt having means to prevent lateral displacement of materials supported thereon.

10 It is a further object of the invention to provide a belt with strongly reinforced selvage edges by which the duration of the belt is much increased and by which all laterally projecting ends of wire are avoided.

15 My invention further relates to arrangements and combinations of parts which will be hereinafter described and more particularly pointed out in the appended claims.

A preferred form of the invention is 20 shown in the drawings in which

Fig. 1 is a plan view of a portion of a belt embodying my improvements;

Fig. 2 is a sectional transverse elevation thereof;

25 Fig. 3 is a diagrammatic end elevation showing a further use of my invention.

Referring to the drawings, I have shown a portion of a conveyer belt formed of spiral wires 10 interlaced to form a mesh-like fabric. Reinforcing wires 12 are inserted between certain of the coils 10 to hold the belt flat and to prevent lateral shrinkage of the belt under tension.

The ends 14 of the wire coils 10 are preferably twisted together, as indicated in Fig. 2, preventing displacement of the coils and causing the ends to be turned in so that they cannot cause injury to clothing or operator.

The coils 10 adjacent the rods 12 are preferably so twisted together at their ends that the twisted ends form an abutment, preventing longitudinal displacement of the rods 12.

45 After the belt is thus constructed and assembled, I turn and compress the edges of the belt to form a reverse fold along each longitudinal edge of the belt, as indicated in Fig. 2. These reverse folds thus provide selvages for the belt which are of double 50 thickness, and thus greatly increases the

wearing quality of the belt along the edge portions where the wear is most severe.

The reverse fold of the selvage is preferably disposed entirely at one side or surface of the belt, thus forming a substantially 55 raised rib or flange along each outer edge of the belt, which effectively prevents lateral displacement of material transported on the belt.

It is also possible to run the belt reversed 60 as indicated in Fig. 3, utilizing the edge folds as guides, cooperating with recessed pulleys or drums 20 and thus causing the belt to travel in a fixed and definite path.

Having thus described my invention and 65 the advantages thereof, I do not wish to be limited to the details herein disclosed, otherwise than as set forth in the claims, but what I claim is:—

1. A conveyer belt formed of interlaced 70 spiral wires extending transversely of said belt, the ends of adjacent wires being twisted together in pairs at the selvages and the selvages being folded lengthwise of the belt to form edge portions of double thickness, 75 the extra thickness being disposed entirely at one side of the belt and constituting retaining means for material transported on said belt.

2. A conveyer belt formed of interlaced 80 spiral wires extending transversely of said belt and reinforcing rods interposed between selected pairs of wires, the end portions of said spiral wires and said reinforcing rods being reversely bent to form thickened selvages for said belt. 85

In testimony whereof I have hereunto affixed my signature.

FRANCIS N. WOODMAN.
